UNITED STATES PATENT OFFICE.

GARFIELD A. WOOD, OF DETROIT, MICHIGAN.

HOISTING AND DUMPING MECHANISM.

1,271,969.

Specification of Letters Patent. Patented July 9, 1918.

Original application filed March 15, 1915, Serial No. 14,480. Divided and this application filed August 21, 1916. Serial No. 115,957.

To all whom it may concern:

Be it known that I, GARFIELD A. WOOD, a citizen of the United States, residing at Detroit, in the county of Wayne and State 5 of Michigan, have invented a new and useful Hoisting and Dumping Mechanism, of which the following is a specification.

It is common practice to tilt the bodies of motor vehicles about pivots located near 10 the rear end of the chassis in dumping coal or other material therefrom, and liquid operated hoisting pistons have been used heretofore for that purpose. The distance the end of the body must be elevated is considerable, 15 which, together with the heavy loads and tendency of the body to swing laterally when elevated (due to twisting of the frame of the chassis when standing on an uneven surface), as well as the generally rough usage 20 to which the devices are otherwise subject, often cause bending of the piston rods. The present invention consists in improved means whereby the lifting force is transmitted from the piston to the body. As 25 shown, the piston rod is hollow, which affords a very greatly increased strength (considering the rod itself) for a given weight, as well as a better connection between the rod and the cross arm than can be secured 30 with the solid rod; it also forms part of the storage reservoir for the oil, thus rendering the whole construction compact. The invention also consists in the reciprocable piston rod, the cross-arm, sheaves carried on the 35 ends of the rod (preferably in such manner as to allow free universal swinging movement transversely and longitudinally of the vehicle) together with depending body arms rigidly secured to the front end 40 of the body on opposite sides of the longitudinally extending propeller shaft, and cables passing over the sheaves in such manner as to cause the front end of the body to rise substantially twice as rapidly as the 45 piston rod. This construction is of very great value inasmuch as it allows the use of a relatively short hoisting cylinder and piston rod (which affords clearance in passing overhead bridges and entering garages) 50 and yet enables the long body to be tilted to a high angle; also because of the fact that the equalizing means which is employed in connection with the cables insures an application of substantially equal lifting force to 55 each of the depending body arms regardless

of warping, lack of accurate adjustment, or the like, and thus largely relieves the pivots of twisting stresses.

Again, the present invention consists in the supplemental cross frame or support formed of spaced metal bars upon which is mounted both a hydraulic cylinder for tilting the body and a pump for supplying liquid to the cylinder, whereby relative deflection of the pump and hoisting cylinder is reduced and leakage in the connections is avoided. The invention further consists in control mechanism for a gear pump supported by the cylinder at a point preferably within convenient reach of the driver, 60 whereby the necessity of modifying such portions of the vehicle as form no part of the hoisting unit is avoided. For a like purpose, the invention also consists in control means for the pump driving clutch supported on the cylinder at a point preferably within reach of the driver. The whole construction is of such nature that it may be manufactured substantially as a standard unit applicable to different makes and styles 65 of chassis with a minimum of special work.

The present application is a division of my application for patent on hydraulic hoisting device, Serial Number 14,480, filed 70 March 15, 1915.

In the drawings, Figure 1 is a fragmentary side view of a motor truck showing one embodiment of my invention, parts being broken away. Fig. 2 is a front elevation corresponding to Fig. 1, parts being 75 omitted. Fig. 3 is a fragmentary side view of the lower end of one of the body brackets and the cable by which lifting force is applied to it. Fig. 4 is a vertical longitudinal section through the hoisting cylinder. Fig. 80 5 is a section of the upper end of the piston at right angles to Fig. 1. Fig. 6 is a section 85 on the line 6—6 of Fig. 1.

Upon the rear end of each of the side frames 1 of the truck is rigidly secured a bracket 2 bearing a pivot 3 about which the body 4 may be swung vertically for dumping purposes; and the body may be provided at its lower side with the longitudinal frame pieces 5 so arranged as to rest, when in lowered position, either on the side frames 1 or in special chairs carried thereby (not shown). This general construction is well known.

The side frames may be cut away at a 110

point forward of the front end of the body as indicated at 6, and may there support the cross bars 8 (preferably angle-irons having their horizontal flanges facing each other) 5 upon which rests the flanged base 9 of a hoisting cylinder 10, the latter of which may be inclined rearwardly and secured to the base by a screw joint 11 (Fig. 4). At its upper end, the cylinder may pass through 10 an expansion chamber or tank 12 which is in free communication with the interior of the cylinder by means of the lower passage 13 and the upper passage 14. The filling opening of the chamber is closed by a plug 15 15, and in the bottom is a gland 16 whereby a discharge pipe 17 may be clamped in place. Various means may be employed for securing the expansion chamber in position; as shown, the upper end of the cylinder is 20 reduced to form a seat 18 (preferably conical) against which the chamber is clamped by a flange 19 of a stuffing box 20 threaded into the interior of the upper end of the cylinder at 21.

25 Mounted to slide in the box 20 is a hollow piston rod 22, the upper end of which is closed by a diaphragm 24; the lower end of the rod is preferably threaded on the annular shoulder 25 of a piston 26, which may 30 be provided with the usual piston rings 28. The piston may have projecting from its lower end the stud 29 that contacts with the base and carries the weight when in lowered position. Free passage of liquid between 35 the inside of the rod and the annular space around it is secured by the holes 30 just above the piston, whereby the interior of the rod may also be utilized for storage purposes. And, in order to admit air to the upper end of the rod to allow the liquid to pass 40 out into the cylinder as the piston rises, there is provided a tube 31, the upper end of which is just below the diaphragm, the lower end opening through the piston wall 45 somewhat below the stuffing box 20 when the piston is in lowermost position. The joint between the piston rod and the box 20 may be sealed by the threaded packing ring 33 and the packing 34.

50 It will be understood that the liquid by which the piston is elevated is normally stored in the annular space above the piston, in the hollow rod and in the expansion chamber. Obviously, it may be pumped 55 from the storage space to the pressure space beneath the piston by various devices, but it is preferred to use a gear pump 36 bolted or otherwise secured at 38 to the base 9 and driven from the propeller shaft 39 of the 60 vehicle by means of clutch mechanism 40 controlled by the levers 41, link 42 and lever 43. The valve shaft of the pump is shown at 44 in Fig. 2 and may be operated by the lever 45, link 46 and lever 47. The reser- 65 voir discharge pipe 17 previously referred

to leads to the intake fitting 48 of the pump, and liquid is discharged into the space beneath the piston through the passage 49 (Fig. 4). As indicated in Fig. 6, the interior of the pump casing may be provided 70 with the passage 50 that leads from the suction side to the pressure side of the gears 51-52 (through the latter of which the propeller shaft passes) and is connected to the pipe 17 by the passage 53. It is also connected to the passage 49 by the three-way valve 54 rigid with the valve shaft 44.

75 It will be observed (Figs. 2 and 6) that the propeller shaft 39 is spaced considerably from the gear 52—this allows the cross-bars 80 8 to sink appreciably (as they do under heavy loads) without inducing bending stresses in the shaft, and also avoids the necessity for accurate alinement of the latter in respect to the gear.

85 The elements shown but not claimed herein are claimed in my application for Patent Serial Number 14,480, referred to above; also my application for Patent Serial Number 14,479, filed March 15, 1915. They are 90 again shown and described in the present application in order to illustrate clearly the peculiar service to which the lifting elements are subjected as well as the purpose of the closure 24.

95 The use of the hollow piston allows a cross bar 60 to be firmly supported by being passed through a hole in the upper end of the rod. Each end of the cross bar is grooved at 61 to receive a shackle 62, portions of which extend downwardly from either side of the bar to support a pivot pin 63, upon the latter of which a second shackle 64 bearing the shaft 65 and pulley 66 is adapted to swing. Secured to the base 9 or 100 other fixed part of the hoist is a shackle 68 to which an equalizing bar 69 is pivoted at 70; and attached to the ends of the latter are the cables 71 that pass over the pulleys 66 and are secured to the brackets 72, rigid with 105 the body. The ends 73 of the shackle 62 are 110 bent to conform to the curvature of the pulley whereby the cable is retained in position thereon.

115 Operation.

120 The parts are normally in the position shown, the upper level of the oil (or other liquid) being slightly below the upper wall of the chamber 12 in order to allow for expansion. When it is desired to hoist the load, the clutch lever and pump valve are manipulated in the proper manner and oil is drawn from the reservoir and forced beneath the piston. As soon as the piston has 125 been elevated a distance sufficient to cause the lower end of the tube 31 to clear the packing ring 33, air rushes in through the tube and the contents of the rod thereafter runs out into the annular space surrounding 130

it and is delivered to the expansion tank as the piston rises. This action maintains a liquid seal over the entrance to the pipe 17 and prevents air from being sucked into the 5 pump. The piston may be lowered by turning the pump valve in position to allow the oil to escape back through the passage 49 and pipe 17 into the tank cylinder and piston rod without passing through the gears 10 51-52, the air escaping through the tube 31. However, before the liquid can possibly overtop the tube, the lower end of the latter will have passed into the packing ring 33, thus preventing any of the liquid from escaping. Since the upper end of the tube is located just beneath the diaphragm, the liquid may rise until substantially the entire capacity of the piston rod is utilized 15 for storage purposes. When it is desired to lower the body, the valve 54 is turned into the position shown (Fig. 6) which allows the liquid to by-pass the pump gears.

It will be seen that the points of attachment of the cables 71 to the brackets 72 are 20 spaced apart from each other transversely of the body which allows application of the equalized lifting forces to the body in such manner as to effectually take up the twisting stresses in the latter. It is also apparent 25 that the equalization of stresses coming to the piston 22 from the opposite ends of the bar 60 avoids the secondary stresses that would otherwise occur therein, and also prevents undue friction of the piston in the 30 members 20-33. The location of the cross bar 60 above the closure 24 is also of importance in that leakage is thus prevented.

It is clear that many changes may be made in the details of construction without departing from the spirit of my invention. I 40 do not, therefore, wish to be limited otherwise than as indicated by the subjoined claims.

I claim:

45 1. Hoisting mechanism comprising a cylinder, a piston slidable therein, a hollow piston rod connected to the piston, said cylinder having an end through which the piston rod passes and to which it closely conforms, whereby the piston rod is guided for movement parallel to the axis of the cylinder, a cross piece carried by the end of the rod remote from the piston, said cross piece projecting laterally in opposite directions 50 from said end, said rod forming a broad support for the cross piece, cables coöperating with the projecting portions of the cross piece for lifting a load, and means for equalizing the stresses in the cables.

60 2. Hoisting mechanism comprising a cylinder, a piston slidable therein, a hollow piston rod connected to the piston, said cylinder having an end through which the piston rod passes and to which it closely conforms, whereby the piston rod is guided for

movement parallel to the axis of the cylinder, a cross piece passing transversely through and projecting laterally in opposite directions from the end of the rod remote from the piston, said rod forming a broad 70 and rigid support for the cross piece, cables coöperating with the projecting portions of the cross piece for lifting a load, and means for equalizing the stresses in the cables.

3. Hoisting mechanism comprising a cylinder, a piston slidable therein, a hollow piston rod connected to the piston, said cylinder having an end through which the piston rod passes and to which it closely conforms, whereby the piston rod is guided for 75 movement parallel to the axis of the cylinder, a fixed closure for the piston rod, said closure being removed somewhat from the end of the rod remote from the piston, a cross piece carried by said end of the rod 80 and projecting laterally in opposite directions therefrom, and means coöperating with the projecting portions of the cross piece for lifting a load.

4. Hoisting mechanism comprising a cylinder, a piston slidable therein, a hollow piston rod connected to the piston, said cylinder having an end through which the piston rod passes and to which it closely conforms, whereby the piston rod is guided for 90 movement parallel to the axis of the cylinder, a cross piece carried by the end of the rod remote from the piston and projecting laterally in opposite directions therefrom, a sheave and a universal support therefor carried on each projecting portion of the cross-piece, cables passing over the sheaves for 95 lifting a load, and means for equalizing the stresses in the cables.

5. In combination with the frame of a motor vehicle and a body tiltable about spaced horizontal pivots located near the rear end of the body, an upright hydraulic hoisting cylinder located forward of the front end of the body, a piston rod slidable therein, said piston rod projecting from the upper end of the cylinder, a cross piece secured to the upper end of the piston rod and projecting transversely of the vehicle, sheaves supported by the outer ends of the cross piece, flexible means passing over the sheaves and secured to the front end of the body, and means other than the body of the cylinder for transmitting stresses from the flexible means to a fixed point near the lower 110 end of said body, whereby said body is relieved of secondary stresses.

6. Hoisting mechanism comprising a cylinder, a piston and piston rod therein, one end of the latter projecting from the cylinder, a cross-piece attached to the projecting end of the piston rod and extending laterally therefrom, the cross-piece being grooved, a shackle seated in said groove, portions of the shackle being bent substan-

tially parallel to each other, a pin passing through the parallel portion of the shackle below and at right angles to the axis of the grooved portion of the cross-piece, a second shackle passing over the pin and having depending ends, a shaft passing through said ends in a direction parallel to the grooved portion of the cross-piece, and a grooved pulley carried by and rotatable in respect to the shaft.

7. Hoisting mechanism comprising a cylinder, a piston and piston rod therein, one end of the latter projecting from the cylinder, a cross-piece attached to the projecting end of the piston rod and extending laterally therefrom, the cross-piece being grooved, a shackle seated in said groove, portions of the shackle being bent substantially parallel to each other, a pin passing through the parallel portion of the shackle below and at right angles to the axis of the grooved portion of the cross-piece, a second shackle passing over the pin and having depending ends, a shaft passing through said ends in a direction parallel to the grooved portion of the cross-piece, and a grooved pulley carried by and rotatable in respect to the shaft, a cable passing over said pulley, said first mentioned shackle having end portions shaped to conform to the curvature of the face of the pulley along the upper side thereof, whereby the cable is prevented from leaving the groove in the pulley.

8. Hoisting mechanism comprising a cylinder, a piston and piston rod therein, one end of the latter projecting from the cylinder, a cross-piece attached to the projecting end of the piston rod and extending laterally therefrom, a shackle seated on and arranged to swing vertically in respect to the cross-piece, a pin passing through the shackle, a second shackle mounted on the pin to swing in a vertical plane at right angles to the swinging movement of the first mentioned shackle, said second shackle having depending ends, a horizontal pin passing through the ends of the second shackle, a pulley rotatable in respect to the pin, a cable passing over said pulley, the ends of the first mentioned shackle being curved downwardly around the periphery of the pulley, whereby the cable is retained in position thereon.

9. In combination with the frame of a motor vehicle and a body tiltable vertically thereon, said body being pivoted on spaced pivots, cables attached to the free end of the body at points removed from each other in a direction parallel to the axis of the pivots, pulleys over which the cables respectively pass, a cross bar upon which the pulleys are supported, a hollow piston upon which the cross bar is carried and by which it may be thrust in a direction to tilt the body, and means for equalizing the stresses

in the cable, whereby secondary stresses in the body and in the piston are avoided.

10. In combination with the frame of a motor vehicle and a body tiltable about spaced horizontal pivots located near its rear end, cables attached to the free front end of the body at points removed from each other in a direction parallel to the axis of the pivots, pulleys over which the cables respectively pass, a cross bar upon which the pulleys are supported, a hollow piston upon which the cross bar is carried and by which it may be thrust in a direction to tilt the body, and means for equalizing the stresses in the cable, whereby secondary stresses in the body and in the piston are avoided.

11. In combination with the frame of a motor vehicle and a body tiltable about spaced horizontal pivots located near its rear end, cables attached to the free front end of the body at points removed from each other in a direction parallel to the axis of the pivots, pulleys over which the cables respectively pass, a cross bar upon which the pulleys are supported, a hollow piston through which the cross bar passes and by which it may be thrust in a direction to tilt the body, and means for equalizing the stresses in the cable, whereby secondary stresses in the body and in the piston are avoided.

12. In combination with the frame of a motor vehicle and a body tiltable vertically thereon, said body being pivoted on spaced pivots, cables attached to the free end of the body at points removed from each other in a direction parallel to the axis of the pivots, pulleys over which the cables respectively pass, a cross bar upon which the pulleys are supported, connections between the cross bar and the pulleys whereby universal swinging movements of the latter in respect to the former are permitted, a piston upon which the cross bar is carried and by which it may be thrust in a direction to tilt the body, a cylinder in which the piston slides, and means for equalizing the stresses in the cable and for transmitting said stresses to a point near the lower end of said cylinder without passing through the body of said cylinder, whereby secondary stresses in the body and in the piston are avoided.

13. A truck comprising a frame, a body tiltable about an axis near the rear end of said frame for dumping purposes, a longitudinally extending propeller shaft for the truck, means rigidly secured to the forward portion of the body and depending therefrom on opposite sides of the propeller shaft, an upright hoisting cylinder carried by the frame, a piston rod slidable in said cylinder, sheaves carried by said piston rod, and cable means passing over said sheaves, said cable means being attached to the lower end portions of the depending means on opposite sides of the longitudinal vertical plane

through the propeller shaft, whereby the body may be tilted.

14. A truck comprising a frame, a body tiltable about an axis near the rear end of said frame for dumping purposes, a longitudinally extending propeller shaft for the truck, means rigidly secured to the forward portion of the body and depending therefrom on opposite sides of the propeller shaft, an upright hoisting cylinder carried by the frame, a piston rod slidable in said cylinder, a cross-arm mounted on the upper end of the piston rod, sheaves suspended on the outer ends of said cross-arm, said sheaves being capable of swinging transversely and longitudinally of the truck, and cable means passing over said sheaves, said cable means being attached to the lower end portions of the depending means on opposite sides of the longitudinal vertical plane through the propeller shaft, whereby the body may be tilted.

15. A vehicle comprising a frame, a body tiltable about alined bearings located on opposite side portions of the rear end of the frame, means fixed to the front end of the body and depending from the latter on opposite sides of the longitudinal central vertical plane thereof, an upright hydraulic hoisting cylinder carried by the frame at a point forward of the front end of the body, a piston rod slidable in said cylinder, sheaves carried by the upper end of said piston rod, and flexible means passing over said sheaves and attached to the depending portions of the means which is fixed to the front end of the body, a pivoted element associated with the flexible means for insuring substantially equal stresses in the portions thereof which pass over the separate sheaves, and means for attaching said pivoted element to a fixed point at a level substantially that of the frame.

16. A truck comprising a frame, a body pivoted near the rear end of said frame to tilt, an upright hydraulic hoisting cylinder carried by the frame at a point forward of the front end of the body, a piston rod slidable therein, and means, including a cross-arm carried by the upper end of the piston rod, sheaves supported on the outer ends of the cross-arm, and flexible means passing about said sheaves, said flexible means having portions attached to the front portion of said body on opposite sides of the vertical central longitudinal plane thereof, and means for equalizing the stresses in the portions of the flexible means.

17. A truck comprising a frame, a body tiltable about an axis near the rear end of said frame for dumping purposes, a longitudinally extending propeller shaft for the truck, means rigidly secured to the forward portion of the body and depending therefrom on opposite sides of the propeller shaft,

an upright hoisting cylinder carried by the frame, a piston rod slidable in said cylinder, sheaves carried by said piston rod, and cable means passing over said sheaves, said cable means having two portions attached at their ends to the corresponding depending portions of the means which is rigid with the forward portion of the body, and means for equalizing the stresses in the two portions of the cable means.

18. A truck comprising a frame, a body tiltable about an axis near the rear end of said frame for dumping purposes, a longitudinally extending propeller shaft for the truck, means rigidly secured to the forward portion of the body and depending therefrom on opposite sides of the propeller shaft, an upright hoisting cylinder carried by the frame, a piston rod slidable in said cylinder, and cable means associated with said piston rod and said depending portions of the means which is rigid with the forward portion of the body whereby said front end of the body is caused to rise more rapidly than the piston rod.

19. A truck comprising a frame, a body tiltable about an axis near the rear end of said frame for dumping purposes, a longitudinally extending propeller shaft for the truck, a pair of body arms secured to the forward portion of the body and depending therefrom on opposite sides of the propeller shaft, an upright hoisting cylinder carried by the frame, a piston rod slidable in said cylinder, sheaves carried by said piston rod on opposite sides thereof, cables attached to the lower ends of the corresponding body arms and passing over said sheaves, and means for equalizing the stress in said cables, whereby the front end of the body is elevated at a more rapid rate than the piston rod and whereby the body is largely relieved of twisting stresses.

20. A vehicle comprising a frame, a body tiltable about alined bearings located on opposite side portions of the rear end of the frame, body arms attached to the front end of the body and depending from the latter on opposite sides of the longitudinal central vertical plane thereof, an upright hydraulic hoisting cylinder carried by the frame at a point forward of the front end of the body, a piston rod slidable in said cylinder, and flexible means associated with said piston rod whereby the front end of the body is elevated at a more rapid rate than said piston rod.

21. A vehicle comprising a frame, a body tiltable about alined bearings located on opposite side portions of the rear end of the frame, body arms attached to the front end of the body and depending from the latter on opposite sides of the longitudinal central vertical plane thereof, an upright hydraulic hoisting cylinder carried by the frame at a

point forward of the front end of the body, a piston rod slidable in said cylinder, a cross-arm supported by the upper end of the piston rod and extending transversely of the vehicle, sheaves suspended on the end portions of said cross-arm and swingable cross-wise of the vehicle, and flexible means associated with said sheaves whereby the front end of the body is elevated at a more rapid rate than said piston rod.

22. A vehicle comprising a frame, a body tiltable about a horizontal axis near the rear end of said frame, an upright cylinder supported by the frame forwardly of the front end of the body, a piston and piston rod slidable therein, said piston rod passing out of the upper end of the cylinder, a cross-piece attached to the projecting end of the piston rod and extending laterally therefrom, the cross-piece being grooved, a shackle seated in said groove, portions of the shackle being bent substantially parallel to each other, a pin passing through the parallel portion of the shackle below and at right angles to the axis of the grooved portion of the cross-piece, a second shackle passing over the pin and having depending ends, a shaft passing through said ends in a direction parallel to the grooved portion of the cross-piece, a grooved pulley carried by and rotatable in respect to the shaft, and a cable passing over said pulley and secured to the body through which force for tilting the latter is transmitted.

23. A vehicle comprising a frame, a body tiltable about a horizontal axis near the rear end of said frame, an upright cylinder supported by the frame forwardly of the front end of the body, a piston and piston rod slidable therein, said piston rod passing out of the upper end of the cylinder, a cross-piece attached to the projecting end of the piston rod and extending laterally therefrom, the cross-piece being grooved, a shackle seated in said groove, portions of the shackle being bent substantially parallel to each other, a pin passing through the parallel portion of the shackle below and at right angles to the axis of the grooved portion of the cross-piece, a second shackle passing over the pin and having depending ends, a shaft passing through said ends in a direction parallel to the grooved portion of the cross-piece, and a grooved pulley carried by and rotatable in respect to the shaft, a cable passing over said pulley, said cable being connected to the front end of the body, said first mentioned shackle having end portions shaped to conform to the curvature of the face of the pulley along the upper side thereof, whereby the cable is prevented from leaving the groove in the pulley.

24. A vehicle comprising a frame, a body tiltable about a horizontal axis near the rear end of said frame, an upright cylinder sup-

ported by the frame forwardly of the front end of the body, a piston rod passing out of the upper end of the cylinder, a cross-piece attached to the projecting end of the piston rod and extending laterally therefrom, a shackle seated on and arranged to swing vertically in respect to the cross-piece, a pin passing through the shackle, a second shackle mounted on the pin to swing in a vertical plane at right angles to the swinging movement of the first mentioned shackle, said second shackle having depending ends, a horizontal pin passing through the ends of the second shackle, a pulley rotatable in respect to the pin, a cable passing over said pulley, said cable being attached to the front end of the body, the ends of the first mentioned shackle being curved downwardly around the periphery of the pulley, whereby the cable is retained in position thereon.

25. In combination with the frame of a motor vehicle and with a driven shaft thereof, a supplemental frame supported on the first-mentioned frame, a hoisting cylinder carried by the supplemental frame, lifting means associated with the hoisting cylinder, a gear pump also supported on the supplemental frame in operative relation to the hoisting cylinder and lifting means, means for driving the gear pump from the driven shaft, whereby relative deflection of the gear pump and hoisting cylinder is reduced and leakage is avoided.

26. In combination with the frame and the propeller shaft of a motor vehicle, a supplemental frame supported on the first mentioned frame, a hoisting cylinder carried by the supplemental frame, lifting means associated with the hoisting cylinder, a pump also supported on the supplemental frame in operative relation to the cylinder and hoisting means, means for driving the pump from the propeller shaft, whereby relative deflection of the pump and hoisting cylinder is reduced and leakage is avoided.

27. In combination with the side bars and the propeller shaft of a motor vehicle, a supplemental frame extending across between the side bars and above the propeller shaft, a hoisting cylinder carried by the supplemental frame, lifting means associated with the hoisting cylinder, a pump also supported on the supplemental frame in operative relation to the cylinder and hoisting means, means for driving the pump from the propeller shaft, whereby relative deflection of the pump and hoisting cylinder is reduced and leakage is avoided.

28. In combination with the frame of a motor vehicle and with a driven shaft thereof, a supplemental frame supported on the first-mentioned frame, a hoisting cylinder carried by the supplemental frame, lifting means associated with the hoisting cylinder,

- a gear pump also supported on the supplemental frame in operative relation to the hoisting cylinder and lifting means, means for driving the gear pump from the driven shaft, whereby relative deflection of the gear pump and hoisting cylinder is reduced and leakage is avoided, means for controlling the pump, and means for controlling the transmission of power from the driven shaft to the gear pump, said controlling means being both located on the cylinder.
29. In combination with the side bars and the propeller shaft of a motor vehicle, a supplemental frame extending across between the side bars and above the propeller shaft, a hoisting cylinder carried by the supplemental frame, lifting means associated with the hoisting cylinder, a pump also supported on the supplemental frame in operative relation to the cylinder and hoisting means, means for driving the pump from the propeller shaft, whereby relative deflection of the pump and hoisting cylinder is reduced and leakage is avoided, means for controlling the pump, and means for controlling the transmission of power from the propeller shaft to the pump, said controlling means being both located on the cylinder.
30. A vehicle comprising a frame, a body tiltable about an axis near the rear end of said frame, an upright hoisting cylinder mounted forwardly of the front end of the body, a piston rod reciprocable therein, means associated with the upper end of the piston rod whereby movement of the latter may cause the body to tilt, a pump for supplying liquid to the cylinder, and control mechanism for the pump, said control mechanism comprising an element supported by the cylinder at substantially the upper level thereof.
31. A vehicle comprising a frame, a body tiltable about an axis near the rear end of said frame, an upright hoisting cylinder mounted forwardly of the front end of the body, a piston rod reciprocable therein,
- means associated with the upper end of the piston rod whereby movement of the latter may cause the body to tilt, a pump for supplying liquid to the cylinder, a valve for 50 supplying liquid to the cylinder, a valve for the pump, and valve controlling means including a hand lever supported on the cylinder.
32. A vehicle comprising a frame, a body 55 tiltable about an axis near the rear end of said frame, an upright hoisting cylinder mounted forwardly of the front end of the body, a piston rod reciprocable therein, means associated with the upper end of the piston rod whereby movement of the latter 60 may cause the body to tilt, a pump for supplying liquid to the cylinder, a driving shaft for the pump, means for connecting and disconnecting said shaft to the pump, 65 and controlling means for said last mentioned means, said controlling means including a hand lever supported on the cylinder.
33. In combination with the side bars and the centrally arranged longitudinally extending propeller shaft of a motor truck, a body tiltable about a horizontal axis near the rear end of the side bars, a cross frame supported on the side bars forwardly of 70 the front end of the body, a hoisting cylinder rising from the central portion of said cross frame, a piston rod reciprocable in said cylinder and projecting from its upper end, there being two open spaces 75 enclosed by the side bars and the cross frame, one on each side of the base of the hoisting cylinder, a pair of body arms secured to the front end portion of the body and each depending into the corresponding open 80 space when the body is lowered, and cable means attached to the lower ends of the body arms and cooperating with the piston rod to transmit lifting stress from the latter to the body.
- In testimony whereof I sign this specification.

GARFIELD A. WOOD.
